US00D840404S

(12) **United States Design Patent** (10) **Patent No.:** **US D840,404 S**
(45) **Date of Patent:** **** Feb. 12, 2019**

(54) **SMART CARD INTERFACE**

(71) Applicant: **NagraStar LLC**, Englewood, CO (US)

(72) Inventors: **William Michael Beals**, Englewood, CO (US); **Hervé Goupil**, Villars sous Yens (CH)

(73) Assignee: **NAGRASTAR, LLC**, Englewood, CO (US)

(**) Term: **15 Years**

(21) Appl. No.: **29/567,144**

(22) Filed: **Jun. 6, 2016**

Related U.S. Application Data

(62) Division of application No. 29/448,761, filed on Mar. 13, 2013, now Pat. No. Des. 758,372.

CLAIM

The ornamental design for a smart card interface, as shown and described.

DESCRIPTION

FIG. 1 is a front perspective view of a smart card interface according to a first embodiment;

FIG. 2 is a front elevation view thereof;

FIG. 3 is an enlarged view of the contacts portion of the smart card interface of FIG. 1;

FIG. 4 is a front perspective view of the smart card interface according to a second embodiment;

FIG. 5 is a front elevation view thereof; and,

FIG. 6 is an enlarged view of the contacts portion of the smart card interface of FIG. 4.

Singular broken lines and portions contained within broken lines are not claimed.

1 Claim, 4 Drawing Sheets
